UNITED STATES PATENT OFFICE.

JULES MAURICE MEYER, OF PARIS, FRANCE.

ATOMIZING DEVICE FOR INTERNAL-COMBUSTION ENGINES.

1,381,730.

Specification of Letters Patent. Patented June 14, 1921.

Application filed January 12, 1920. Serial No. 351,067.

To all whom it may concern:

Be it known that I, JULES MAURICE MEYER, engineer, citizen of the French Republic, residing at Paris, France, have invented certain new and useful Improvements in an Atomizing Device for Internal-Combustion Engines, of which the following is a specification.

The invention relates to means for injecting, during the working of an explosion engine and preferably when the said engine attains a determined temperature, in the cylinder or the cylinders of the said engine a determined amount of atomized water.

15 In the accompanying drawings,

Figure 1 shows a vertical section of an injecting apparatus constructed according to the invention.

Fig. 2 shows a horizontal section on line 20 A B Fig. 1.

Fig. 3 shows in vertical section a part of a modification of the said injecting apparatus.

On the drawing, 1 is the body or casing of the apparatus; the lower part of the said body being internally screw-threaded for receiving a screw plug 2. The said plug is provided with a shoulder 3 and a screw-threaded end 3^a which is to be screwed on 30 the suction pipe of the engine, between the engine and the carburetor. The upper part of the body 1 is also internally screw-threaded. In this screw-threaded part is screwed a screw 4 provided with a jam nut 4^a.

35 The water is fed to the apparatus through a pipe 5 opening in an axial bore 6 of the body 1. The walls of the body 1 are provided on one side with an opening 7 for the passage of a lever 8, and on the other side 40 with two openings separated by a projection 10, as shown in Fig. 2, to which projection the lever 8 is hinged by means of a bolt 11.

On the Figs. 1 and 2 of the drawings the lever is shown as having the form of a fork, 45 the ends of the two branches of the said fork being hinged to the projection 10. The other end of the lever is provided with a hole in which is fixed one of the ends of a spring 12; the other end of the said spring 12 being fixed to a washer 13 engaged on the screw 4 and maintained in its position by the jam-nut 4^a.

In the body is mounted the feeding device 50 14; the upper part of which is constituted by a stem engaging in the axial bore 6 and provided with longitudinal grooves 15. The

said grooves are of suitable depth, but their depth is greater near the upper part of the stem. The grooves allow the water fed through the pipe 5 to flow down through the 60 axial bore 6.

The feeding device comprises in its middle part a collar 16 which is embraced by the two branches of the lever 8, and at its lower part a head 18 having its upper part of hemispherical form and its lower part of conical form. A disk 17 provided in its center with a hole is mounted in the body and is fixed between the said body and the nut 2. The said disk is used as a seat for the hemispherical part of the said head 18.

The screw 4 has a sufficient length for allowing the control of the feeding of water through the pipe 5.

The openings in the walls of body 1 are 75 used as air-holes.

In the modification shown in Fig. 3 the lever 8, instead of having two branches embracing a collar 16 of the device 14 passes through a hole 16^a provided in the said device.

It is obvious that when the engine is running, if the pipe 5 is connected to a water tank mounted at a suitable level and if the lever 8 is actuated for moving the device 14 85 downward, the water flows through the grooves 15 and falls on the head 18. The lever 8 is acted upon by a system of interconnected levers and links (not shown) adapted to be operated from the driver's seat of the motor 90 vehicle. The said head being lowered, air can pass through the hole of the disk 17 and, for each suction stroke of the engine, water will be drawn into the cylinder or cylinders. As soon as the said lever is released, it is 95 returned by the spring 12 to its normal position, and the device 14 is moved therewith until the head 18 bears on the disk 17 and closes the hole of the said disk.

Having now particularly described and 100 ascertained my invention, and in what manner the same is to be performed, I declare that what I claim is:

1. A device of the class described comprising a casing adapted to be connected to the 105 suction pipe of an internal combustion engine, said casing having a water inlet, a bore communicating therewith, and a valve cage having air openings formed therein, a feeding device in said casing having a stem located in said bore, said stem being provided with tapered grooves and a valve head con-

connected to said stem for controlling communication between said valve cage and the suction pipe, and means for moving said valve head and stem to permit the suction of the 5 engine to draw air through said openings and to expose the tapered parts of said grooves to the action of said air whereby the water contained therein may be atomized and mixed with the fuel mixture in the suc- 10 tion pipe.

2. A device of the class described comprising a two part casing, one of said parts adapted to engage the suction pipe of an internal combustion engine and the other 15 part having a longitudinal bore, a water inlet and air openings formed therein, a plate

located between said parts having a valve seat, a valve adapted to engage said seat, a stem having longitudinally tapered grooves projecting from said valve and extending 20 into said bore, and means acting on said stem for opening and closing said valve and simultaneously exposing or covering said grooves.

In testimony whereof I have hereunto set 25 my hand in presence of two subscribing witnesses.

JULES MAURICE MEYER.
